GRINDING MACHINE FOR RAILWAY
TRACKS

Henry H. Talboys, Milwaukee, Wis., assignor to
Nordberg Manufacturing Co., Milwaukee, Wis.,
a corporation of Wisconsin

Application November 2, 1932, Serial No. 640,792

9 Claims. (Cl. 51—178)

My invention relates to an improvement in grinding machines for railroad tracks and has for one purpose the provision of a simple, light and efficient grinder which may be mounted upon or moved along a railway track and which may be readily removed from the track. Another object is the provision of an improved grinding member together with guard and handle means therefor. Another object is the provision of improved means for maintaining the track grinder parallel to the single rail and for insuring that it travel readily along said rail. Another object is the provision of an improved release for preventing breakage of the flexible shafts employed. Other objects will appear from time to time in the course of the specification and claims.

I illustrate my invention more or less diagrammatically in the accompanying drawings, 20 wherein—

Figure 1 is a side elevation;

Figure 2 is an end elevation;

Figure 3 is a section on the line 3—3 of Figure 2;

Figure 4 is a section on the line 4—4 of Figure 3;

Figure 5 is a section on the line 5—5 of Figure 3;

Figure 6 is a section on the line 6—6 of Figure 1;

Figure 7 is a plan view of the grinding member shown at the left of Figure 1;

Figure 8 is a section on the line 8—8 of Figure 1;

Figure 9 is a section on the line 9—9 of Figure 8; and

Figure 10 is an enlarged section on the line 10—10 of Figure 1.

Like parts are indicated by like symbols throughout the specification and drawings.

Referring to the drawings, A A indicate the rails of a track. Spanning these rails is the transverse shaft or tube A¹ which is provided at one end with any suitable roller or member A² of insulating material. Rubber is a practical material for this purpose. The tube A¹ is removably secured at its opposite end to a frame generally indicated as B. This removable connection is illustrated in Figure 10. I may employ for example spacing collars A¹⁰, and cotter pins A¹¹ for holding the shaft A¹ in position. Upon movement of the cotter pins the shaft may be readily endwise removed from the frame.

The frame may include longitudinally extending angle members B¹ which are connected

as by the horizontal channels B². The ends of the channels B² may be connected by the arcuate members B³. Downwardly depending from the angles B¹ are the flanges B⁴ to which the shaft or tube A¹ is actually secured. Other depending flanges are the members B⁵ which may receive the transversely extending axles B⁶ of the flanged rollers B⁷. These rollers B⁷ are shown as having oppositely inclined faces B⁸ and flanges B⁹. As will appear in Figure 2 the tendency of such a roller is to maintain the roller in central position on the rail. This makes the machine easier to push, and prevents the roller from crowding over and prevents any substantial bearing of the flanges B⁹ against the sides of the ball of the rail. The rollers B⁷ may be insulated from the axles B⁶ as by washers and sleeves B¹⁰ of insulating material.

C generally indicates any suitable motor structure mounted on the above frame work, 20 preferably with the axis of rotation of the motor parallel with the extension of the rails. It includes a shaft C¹ carrying a fly-wheel C² which serves also as a drive wheel. The fly-wheel C² is shown as having passing about it any suitable driving belt C³ which passes also about the driven pulley D. The driven pulley D is provided with a shaft or axle D¹ shown as mounted in roller bearings D² within a cylindrical sleeve D³ mounted on any suitable bracket members D⁴ pivoted 25 as at D⁵, to the frame or base members D⁶. D⁷ is a lever which, in cooperation with the spring D⁸, tends to hold the pulley D in belt tightening and thus in driving position. D⁹ indicates any suitable means for securing the spring D⁸ to an angular member D¹⁴ secured to the arcuate members B³. D¹⁰ is a driving connection for the flexible shaft member D¹¹ which in turn is surrounded by a flexible cover D¹².

Interposed between the pulley D and the shaft D¹ is the following releasable driving connection. The shaft D¹ has an enlarged portion E upon which is secured and held against rotation the clutch collar E¹ which is provided with notches E² in which seat locking balls or rollers E³. The pulley D is provided with an opposed clutch member E⁴ similarly notched as at E⁵ to engage said balls, the pulley D being loosely mounted upon the enlarged portion E of the shaft as illustrated in Figure 3. The pulley is recessed as at E⁶ and opposed to said recess and extending about the cylindrical portion E⁷ of the pulley D is the coil spring E⁸. This spring is compressed between the pulley D and the abutment block E⁹ held by the locking member or nut E¹⁰. The nut 55

in turn is locked against rotation as by the ball E¹¹ seating in the groove E¹² and a screwthreaded outward extension E¹³ of the enlarged portion E of the shaft D¹. The ball E¹¹ is held in place as by a spring E¹⁴. It will be understood that the spring E⁸ tends to thrust the pulley, which is free to rotate and is slidably mounted on the enlarged portion E of the shaft, toward the clutch collar E¹. This grips the balls E³ in the opposed notches E² and E⁵. Thus a driving connection is maintained. If the grinding tool or the flexible shaft is subjected to some predetermined excess strain, causing it to slow down its rotation and therefore causing a slowing of the rotation of the member E¹, the balls will snap out of the slots E² and E⁵ and relative rotation of the pulley D and the member E¹ will be permitted, since the spring E⁸ will permit the pulley D a certain measure of movement along the shaft E. This overload release serves to protect the flexible shaft from damage, in case the grinding element should become snagged and stop suddenly when working.

Whereas the present structure may be employed with a variety of grinding members, I illustrate as a particular application of its use, a novel and efficient grinding wheel which is useful for grinding the flow from the switch point and the adjacent stock rail. This switch grinding cup wheel includes a cup-shaped grinding element G mounted on a hub or shaft G¹ and compressed between two locking or holding members G² by the nut G³. G⁴ indicates a sleeve provided with roller or ball bearings G⁵ in which rotates the shaft G¹, with its integral portion G⁶. Associated with the sleeve G⁴ is the arcuate walled guard G⁷, provided with a manually operable handle G⁸. This guard is closed at its rear as at G⁹ but is open at the front. The guard terminates, as at G¹⁰, adjacent or slightly below the axis of rotation of the grinding element G. The guard is herein shown as having outwardly projecting brackets G¹¹ upon which are mounted rollers G¹². The guard structure assembly is secured to the bearing sleeve G⁴ as by the clamp G¹³ about the split sleeve G¹⁴ which may be welded to the wall G⁹. These rollers may be made of insulating material.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

A typical embodiment of my invention is a grinding or cutting machine which is particularly applicable for use on the rails of a railway track. The motor is aligned over one rail of such a track and the shaft A¹ provides a supporting connection with the other rail. The inclined surfaces B⁸ of the rollers B⁷ tend to align the rollers on the rails A, with the flanges B⁹ out of contact with the sides of the rail.

It is not uncommon, in devices of this kind, where a variety of working parts are employed with the flexible shaft, to have a working member snag or jam. In such case the flexible shaft is frequently damaged or destroyed. I provide the overload release above described in which the driving connection between the pulley D and the driven member D¹ includes a pair of opposed

slotted discs or tracks E¹ E⁴, urged toward each other as by the spring E⁸, and normally maintained in driving connection by the balls E³. These balls may be carried and kept properly separated as by the guide disc or cage E²⁰. When the load on the flexible shaft D¹¹ becomes too great, the overload release spring E⁸ compresses, allowing the overload release balls E³ to roll out of their slots, thus allowing the pulley to turn until the load is released, when it again picks up and turns the flexible shaft core members D¹, E.

As an example of a practical grinding element I illustrate a grinding cup which is particularly adaptable for grinding off switches. The rollers G¹² may engage both rails of the switch, thus aligning the grinding cup G in proper position. The guard G⁷ protects the user from the grinding cup, but permits the grinding cup to engage the face of the rail. The handle G⁸ is shown as mounted on a plurality of handle brackets G²⁰ and is arcuate, extending about an arc of about 180°. This permits it to be grasped readily from a variety of angles and also makes it easy to hold it with two hands, if that becomes necessary. The result is a particularly efficient tool for grinding the flow of metal which occurs both on the stock rail and on the switch point, from the rolling of the car wheels. Such flow, if allowed to become too great, may interfere with the proper closing of the switch point against the stock rail, thus allowing a flange of the car wheels to "split the switch", thereby causing a wreck or derailment.

In order to facilitate packing for shipping of grinding machines the transverse shaft A¹ may be removably mounted in the depending flanges B⁴ as illustrated in Figure 10. I may employ spacing collars A¹⁰ and cotter pins A¹¹ for keeping the shaft A¹ in position.

Where the claims call for means for bridging a pair of adjacent rails it will be understood that a distance between rails of substantially less than the normal track span is intended. Such limitation will be understood in connection with Figure 8 which shows rails closely adjacent, as at or near a switch, in contrast to the full span of rails of a track. One of the purposes of my invention is to provide means for grinding the sides of rails, wherein the grinding element may penetrate between two closely adjacent rails, the supporting means engaging the tops of and spanning the rails and serving not merely to support but to guide the grinding element and to maintain its axis horizontal.

The arcuate members or hoops B³, as shown for example in Fig. 2, are associated with the channels B². As shown in Fig. 2, they surround a motor structure or track working equipment and are adapted to protect it in case the device is rolled off the rail. A rolling action may readily take place if the operator simply lifts up on the outer end of the member A¹. The whole device may then be readily rolled out of the way to one side of the track, in case a train has to pass. The members B³ extend entirely above the top of the power plant C, making it easy to roll the device entirely over into an upside down position. The members B³ are strengthened by an attachment to the longitudinal carrying members B² shown in section in Fig. 2 and in side elevation in Fig. 1. No. D¹⁴ may serve as an attachment reinforcement for strengthening.

I claim:

1. In a track working machine, a motor and means for supporting it upon a track, a flexible
